[57] CLAIM

The ornamental design of a rotatable display rack, substantially as shown and described.

DESCRIPTION

FIG. 1 is a front perspective view of a rotatable display showing my new design, the hooks being shown in broken lines for illustrative purposes only;

FIG. 2 is a rear elevational view thereof.

The two sign supports are of no substantial thickness and are centered on the upper surface of the rack.

FIG. 1

FIG. 2
